UNITED STATES PATENT OFFICE.

HORACE W. HACKER, OF CHICAGO, ILLINOIS.

METHOD OF CORRECTING THE WORKING THICKNESS OF A PRINTING ELEMENT.

1,316,888.

Specification of Letters Patent. Patented Sept. 23, 1919.

Application filed June 20, 1918. Serial No. 241,083.

To all whom it may concern:

Be it known that I, HORACE W. HACKER, a citizen of the United States, residing at Chicago, in the county of Cook and State of Illinois, have invented a certain new and useful Improvement in Methods of Correcting the Working Thickness of a Printing Element, of which the following is a full, clear, concise, and exact description.

My invention relates to printing and has for its object the provision of a method for making the working thickness of a printing element substantially correct throughout the printing area. The method consists in measuring the working thickness of the printing element at a multiplicity of places substantially evenly distributed through the printing area and disposing patches of compensating thicknesses respectively in working alinement with the measured portions of the printing element.

The method of the invention is of particular service in correcting the composite working thickness of a printing plate and its mounting although the invention is not to be limited to such a use. I preferably temporarily place a mounting sheet upon the printing plate and measure through the mounting sheet the composite working thickness of the printing plate and its mounting at a multiplicity of places which are substantially evenly distributed throughout the printing area. I dispose patches of compensating thicknesses upon the mounting sheet in positions respectively similar to the measured portions of said plate and its mounting and then relocate the patch supporting mounting sheet between the printing plate and its mounting with the compensating patches thereon respectively in working alinement with the measured portions of the printing plate and its mounting. In order to avoid ridges the patches are laterally spaced apart to afford gaps therebetween.

I will explain my invention more fully by reference to the accompanying drawings showing the preferred embodiment thereof and in which Figure 1 illustrates a printing plate and its mounting temporarily assembled by a few tacks and above the plate there is shown a mounting sheet which is to be placed temporarily upon the plate; Fig. 2 is a cross sectional view of a part of the plate and a portion of its mounting; Fig. 3 illustrates the mounting sheet placed tem-

porarily upon the plate; Fig. 4 is a sectional view showing portions of the parts shown in Fig. 3; Fig. 5 is a view illustrating one device that may be employed for measuring the working thickness of a printing element; Fig. 6 is a view of a part of the mechanism shown in Fig. 5, portions being shown in section and a part being removed to illustrate the mechanism; Fig. 7 is a sectional view illustrating a detail of construction of the measuring device shown in Fig. 5; Fig. 8 is a sectional view of a part of the plate and block with compensating patches and their mounting sheet upon the plate; Fig. 9 is a perspective view illustrating a mounting sheet with the patches thereon between the plate and block that are illustrated in separated relation; and Fig. 10 is a sectional view of a part of the plate and block with compensating patches and their mounting sheet between the plate and block.

Like parts are indicated by similar characters of reference throughout the different figures.

The drawings illustrate the employment of the method of my invention in conjunction with a printing plate 1 which is temporarily mounted upon the wooden block 2 by means of a very few tacks 3. The temporarily mounted plate and its mounting block are placed in a planer which planes the bottom face of the block to bring the aggregate working thickness of the plate and block two-one-thousandths of an inch below type high thickness at the places of greatest aggregate thickness. A thin coating of printer's ink is then placed upon the printing face of the plate 1 whereafter a mounting sheet 4 is applied to the plate and is temporarily held thereon by the ink. This mounting sheet is preferably French folio paper, having a thickness of two-one-thousandths of an inch. This paper is desirably supplied by those who practice the method in large sheets which are ruled or perforated along crossed lines 5 in order that sheets of approximately suitable dimensions may be quickly formed.

The printing plate 1, the mounting block 2 therefor, and the mounting sheet 4 upon the plate are next placed in a thickness measuring machine to determine to what extent the aggregate working thickness of the plate and mounting is lacking. A machine which would readily serve this purpose is disclosed in the patent to James B. Replogle,

1,171,646, dated February 15, 1916. This machine includes an engaging element or bed 6 (Fig. 5) upon which the block 2 is supported. A follower 7 is mounted to be engageable with the printing face of the printing plate, the bottom face of the follower being flat if the printing plate is flat or otherwise conforming to the printing face of the printing plate. This follower is universally mounted in a follower support 8. The follower support is suitably mounted so that it may be lifted at its forward end to lift the follower to permit the plate and its mounting to be interposed between the follower and the support 6. A micrometric gage 9 is mounted independently of the follower carrier 8 upon a bracket structure 10. The plunger 11 of the micrometric gage rests upon the top of the follower and is maintained in engagement therewith by a spring 12 (Fig. 6). The plunger is provided with a rack 13 in actuating relation to a train of gears 14, the final wheel of the gear train being upon a shaft that carries an indicating needle 15. A weight 16 is provided for applying the follower 7 to the plate 1 with heavy working-like pressure to simulate as far as possible the actual condition which obtains when the plate is in printing operation. This weight is carried upon the forward end of a crank arm 17 in fixed relation with a rotatable sleeve 18 having a bore co-axial with a shaft 19. The intermediate portion of the sleeve 18 is enlarged and has a circular periphery which is eccentric with respect to the shaft 9, this eccentric being thus in fixed angular relation with the crank arm 17. The eccentric portion of the sleeve 18 is surrounded by an eccentric strap 20 at the lower end of a pitman 21 whose upper end is connected with an intermediate portion of the follower support 8 which is preferably mounted upon the bracket 10 at 8° . When the crank arm 17 is raised the eccentric will be shifted to raise the front end of the follower support 8 and when the crank arm is lowered the follower support will be consequently lowered. The weight 16, through the intermediation of the crank arm 17, the pitman 21, and the follower support 8, presses the follower 7 upon the mounting sheet 4 and the plate 1 and block 2 beneath the mounting sheet with the desired degree of heavy working-like pressure whereby the particular portion being measured is brought to the thickness it will assume in its working environment. Each time a new measurement is taken the forward end of the crank arm 17 is lifted to permit the desired repositioning of the plate beneath the follower, whereafter the crank arm is generally lowered until the follower rests upon the mounting sheet, whereupon the arm will be released to permit the weight to press the follower 7 upon the

mounting sheet with the requisite pressure. The plunger 11 of the micrometric gage will follow the movement of the follower to bring the indicating needle 15 to the working thickness indicating position which may be the correct thickness or less than the correct thickness. 70

The measurements are taken at a multiplicity of places substantially evenly distributed throughout the printing area. A patch 22, of compensating thickness is placed upon the mounting sheet at each place where the working thickness is deficient. I desirably employ a tray 23 in the compartments of which patches of varying thicknesses are located. One compartment (labeled one-one-thousandth) may contain patches that are one one-thousandth of an inch thick, another compartment may contain patches that are two one-thousandths of an inch thick, another compartment may contain patches that are three one-thousandths of an inch thick, etc. The thickness of each patch may be printed thereon or the patches may be of different colors, each color corresponding to a thickness. For example, patches of a pink color would be one-one-thousandth of an inch thick, white patches two one-thousandths of an inch thick, and blue patches three one-thousandths of an inch thick, etc. 90 The deficiency in the working thickness occurring at each place measured may be penciled on the mounting sheet, as indicated in Fig. 3, and when there is no deficiency such a condition may also be noted on the mounting sheet for the sake of assurance. Fig. 3 indicates two places where the working thickness is one one-thousandth of an inch deficient, three places where such thickness is two one-thousandths of an inch deficient, 105 five places where it is three one-thousandths of an inch deficient, three places where it is four one-thousandths of an inch deficient, one place where it is five one-thousandths of an inch deficient, and six places where it is 110 not deficient. No compensating patches are placed upon the mounting sheet where the working thickness is not deficient. A pink patch of paper one one-thousandth of an inch thick is pasted on the mounting sheet at 115 each place where the working thickness is one one-thousandth of an inch deficient; a white patch of paper two one-thousandths of an inch thick is pasted on the mounting sheet at each place where the working thickness is two one-thousandths of an inch deficient; a blue patch of paper three one-thousandths of an inch thick is pasted on the mounting sheet at each place where the working thickness is three one-thousandths of an inch deficient; a red patch of paper four one-thousandths of an inch is pasted on the mounting sheet at each place where the working thickness is four one-thousandths of an inch deficient; and a green patch of paper five 120

one-thousandths of an inch thick is pasted on the mounting sheet at each place where the working thickness is five one-thousandths of an inch deficient. These patches of paper are thus disposed in positions respectively similar to the measured portions of the plate and its mounting and after this step in the method has been accomplished the tacks 3 are removed and the printing plate is lifted 10 from its mounting block whereafter the patch supporting mounting sheet is relocated from the top of the printing plate to a place between the printing plate and its block (Fig. 7) and in such position that the compensating patches on the mounting sheet are respectively in working alinement with the measured portions of the printing plate and its mounting; that is, these patches are so located that they are underneath those 15 positions which they initially occupy above the plate. After the mounting sheet has been properly relocated from the top of the printing plate the printing plate is firmly secured to its mounting block. These 20 patches thus bring the printing plate to a proper working thickness throughout its printing area. The patches are desirably laterally spaced apart to afford the gaps therebetween that are illustrated in Fig. 7 25 to prevent the formation of ridges at the adjacent edges of adjacent patches. By means of my invention patches of compensating thickness are respectively disposed in working alinement with the measured portions 30 of the printing element, the process being very simple and accurate.

While I desirably employ patches each individual to a measured portion of the printing element that is deficient in working 40 thickness, I do not wish to be limited to such individual patches.

While I have herein shown and described one form of apparatus with which to practise my method and one type of printing 45 element involved in the method, I do not wish to be limited to such apparatus nor to the nature of printing element in connection with which the method is used, but having thus described my invention I claim as new 50 and desire to secure by Letters Patent the following:—

1. The method of making the composite working thickness of a printing plate and its mounting substantially correct throughout 55 the printing area which consists in temporarily placing a mounting sheet upon the printing plate; measuring through the mounting sheet the composite working thickness of the printing plate and its mounting 60 at a multiplicity of places substantially evenly distributed throughout the printing area; disposing patches of compensating thicknesses upon said mounting sheet in 65 positions respectively similar to the measured portions of said plate and its mounting; and

relocating said patch supporting mounting sheet between the printing plate and its mounting with the compensating patches thereon respectively in working alinement with the measured portions of the printing 70 plate and its mounting.

2. The method of making the working thickness of a printing element substantially correct throughout the printing area which consists in temporarily placing a mounting 75 sheet upon the printing element; measuring through the mounting sheet the working thickness of the printing element at a multiplicity of places substantially evenly distributed throughout the printing area; disposing patches of compensating thicknesses 80 upon said mounting sheet in positions respectively similar to the measured portions of the printing element; and relocating said patch supporting mounting sheet with the 85 compensating patches thereon respectively in working alinement with the measured portions of the printing element.

3. The method of making the composite working thickness of a printing plate and its mounting substantially correct throughout 90 the printing area which consists in temporarily placing a mounting sheet upon the printing plate; measuring through the mounting sheet the composite working thickness 95 of the printing plate and its mounting at a multiplicity of places; disposing patches of compensating thicknesses upon said mounting sheet in positions respectively similar to the measured portions of said 100 plate and its mounting; and relocating said patch supporting mounting sheet between the printing plate and its mounting with the compensating patches thereon respectively in working alinement with the measured 105 portions of the printing plate and its mounting.

4. The method of making the working thickness of a printing element substantially correct throughout the printing area which 110 consists in temporarily placing a mounting sheet upon the printing element; measuring through the mounting sheet the working thickness of the printing element at a multiplicity of places; disposing patches of 115 compensating thicknesses upon said mounting sheet in positions respectively similar to the measured portions of the printing element; and relocating said patch supporting mounting sheet with the compensating 120 patches thereon respectively in working alinement with said measured portions of the printing element.

5. The method of making the composite working thickness of a printing plate and its mounting substantially correct throughout 125 the printing area which consists in measuring such composite working thickness at a multiplicity of places substantially evenly distributed throughout the printing area; 130

1
and disposing patches of compensating thicknesses upon a mounting sheet and between the plate and its mounting and respectively in working alinement with the 5 measured portions of the printing element and mounting.

6. The method of making the working thickness of a printing element substantially correct throughout the printing area which 10 consists in measuring the working thickness of the printing element at a multiplicity of places substantially evenly distributed through the printing area; and disposing patches of compensating thicknesses upon a 15 mounting sheet and respectively in working alinement with the measured portions of the printing element.

7. The method of making the composite working thickness of a printing plate and 20 its mounting substantially correct throughout the printing area which consists in temporarily placing a mounting sheet upon the printing plate; measuring through the mounting sheet the composite working thickness of the printing plate and its mounting 25 at a multiplicity of places substantially evenly distributed throughout the printing area; disposing laterally spaced apart patches of compensating thicknesses upon 30 said mounting sheet in positions respectively

similar to the measured portions of said plate and its mounting; and relocating said patch supporting mounting sheet between the printing plate and its mounting with the compensating patches thereon respectively in working alinement with the measured portions of the printing plate and its mounting.

8. The method of making the working thickness of a printing element substantially 40 correct throughout the printing area which consists in temporarily placing a mounting sheet upon the printing element; measuring through the mounting sheet the working thickness of the printing element at a multiplicity of places substantially evenly distributed throughout the printing area; disposing laterally spaced apart patches of compensating thicknesses upon said mounting sheet in positions respectively similar to the 45 measured portions of the printing element; and relocating said patch supporting mounting sheet with the compensating patches thereon respectively in working alinement with the measured portions of the 50 printing element.

In witness whereof, I hereunto subscribe my name this 29th day of May A. D., 1918.

HORACE W. HACKER.
